5 Claims. (Cl. 179—171.5)

In modulator arrangements there occur with constant grid biasing potential variations of the high-frequency voltage furnished and variations of the degree of modulation. It is known that when feeding the modulation arrangement from an A. C. network to also derive the biasing grid potential of the modulation tube from the network by means of a rectifier. Furthermore, it is also known to apply a fixed grid biasing potential in series to the biasing potential which varies with the voltage of the network. With this arrangement, variations of the plate potential can be compensated such that the delivered high-frequency voltage and the degree of modulation remain constant.

The variations of the operating voltage in tube transmitters having separate oscillator and modulator may be compensated for by using for the biasing potential of the modulation tube a voltage varying with the network voltage in combination with a fixed voltage. It is proposed in accordance with the invention to obtain the variable biasing potential of the modulation tube by rectification of the current from an oscillator fed from the same network.

As compared with the known arrangement, the arrangement according to the invention has the advantage that it furnishes the same favorable results in the case of A. C. or D. C. networks. In the hitherto known arrangement the use of an A. C. supply network was a necessary condition. It would be possible where a D. C. network is present to apply the line voltage to a potentiometer and to derive therefrom the variable biasing potential and the plate potential. But, such an arrangement appears unfeasible in view of the resultant large decrease of the voltage available for the anode. Furthermore, in D. C. supply arrangements the negative pole of the plate potential is ordinarily connected to the positive pole of the heating voltage which condition does not readily permit the insertion of a resistor as potentiometer element for supplying the biasing potential.

In accordance with a further feature of the invention, the oscillator provided for supplying the variable biasing potential is utilized at the same time as excitor or control oscillator for a modulator arrangement. The circuit arrangement assumes an especially advantageous form if this oscillation generator is used as oscillator for the modulator arrangement for which it also furnishes the variable biasing potential. This affords the further advantage that other variations of the high-frequency voltage can likewise

be compensated such as produced by changes in the circuit elements of the oscillator. This compensation is possible since the control potential is a direct function of the high-frequency exciter voltage of the modulator.

The invention will be explained in greater detail with reference to Figures 1 and 2 of the accompanying drawing. Figure 1 shows a tube transmitter in which the oscillator G and the modulation tube M are separate arrangements, 5 while Figure 2 shows a modification of the invention. In Figure 1 the audio-frequency modulation voltage NF is applied to the grid circuit of the modulation tube by means of the transformer T_{NF} . The high-frequency potential HF supplied by the oscillator is applied to said grid circuit by means of the transformer T_{HF} . The oscillator is represented as tube generator with feed back. Modulator and generator are assumed to be fed from the same network. In the grid modulation 10 circuit shown, the non-linear part of the $I_a - V_g$ characteristic is utilized. If the plate potential varies for instance by $+\Delta V_a$, the working point changes its location. This entails a variation of the delivered high-frequency potential, and of 15 the degree of modulation. To provide compensation it is necessary to impress upon the grid an additional biasing potential equal to $-D \cdot \Delta V_a$ where D is the reciprocal of the amplification factor of the tube. Thus, due to the plate potential being likewise increased by $+\Delta V_a$, the high-frequency amplitude will be increased in the oscillator tube by a value proportional to ΔV_a . A high-frequency current is derived from the plate circuit of the oscillator tube by means of a further winding of the transformer T_{HF} , said current being rectified by a tube detector or dry-contact rectifier. The rectifier shown is a dry contact rectifier bridge $G1$ by which a variable direct biasing potential is obtained whose variation in operation is likewise proportional to ΔV_a . If this voltage is caused to coact with the direct biasing potential B of the modulation tube the variations of the plate potential can by proper proportioning be compensated for the high-frequency potential applied to the load R_a across the output transformer T_A and the modulation factor remain constant. 20

Another embodiment of the invention is shown in the example of Figure 2. In this figure the output potential of the oscillator G is applied to the grid circuit of the modulator M by means of connections from terminals 1, 2 to the output of the transformer T_{HF} , or it may be applied to any other load such as another modulator or a 25

de-modulator by means of terminals 1, 2. As compared with the circuit of Figure 1, a considerable simplification resides in that the variable grid biasing potential is derived directly from the oscillation generator. As shown, rectification of the feed back potential is accomplished by the grid-cathode path of the generator tube. The direct current obtained in the grid cathode circuit by the rectification between the grid and cathode and flowing through resistor R_g causes a potential to be stored in the condenser C_g . This potential is applied through resistor R in series with biasing battery B to the grid of modulator tube M . Resistor R and condenser C act as a filter network for the direct current obtained from the oscillator circuit. When using a multi-electrode tube as oscillator, the rectification may, however, also be obtained through other suitable electrodes. The oscillator G supplying the variable biasing potential for the modulator M need not be used necessarily as a generator of the carrier for the modulator M as any other available source of high frequency energy may be applied to terminals HF if desired.

25 I claim:

1. A circuit arrangement including a first thermionic discharge tube having a control grid and serving as a generator for high frequency oscillations, a second thermionic discharge tube having a control grid and serving as a modulator tube for high frequency oscillations, means for applying a biasing potential to said control grid of said second tube, means for rectifying a portion of the oscillations as generated by said first tube and means for applying said rectified oscillations as an added bias to the control grid of said second tube.

2. A circuit arrangement including a first thermionic discharge tube having a control grid and serving as a generator for high frequency oscillations, a second thermionic discharge tube having a control grid and serving as a modulator tube for high frequency oscillations, means for applying high frequency oscillations and means for applying modulating potentials to said control grid of said second tube whereby said high frequency oscillations are modulated by said modu-

lating potentials, means for applying a biasing potential to said control grid of said second tube and means for rectifying a portion of the unmodulated oscillations generated by said first tube and means for applying said rectified oscillations as an added bias to the control grid of said second tube. 5

3. A circuit arrangement comprising an oscillator circuit including a thermionic discharge tube having a control grid and a cathode, a modulator circuit including a thermionic discharge tube having a control grid, means for applying high frequency oscillations to the control grid of said modulator tube, means for also applying modulating potentials to said grid, means for 15 applying a fixed bias to the grid of said second tube and means for applying a variable added bias to the grid of said second tube said last mentioned means comprising a connection including a resistance and a condenser connected 20 in shunt thereto between the control grid and cathode of said oscillator tube and a connection from the end of said resistance adjacent the control grid of said oscillator tube to the control grid of said modulator tube whereby the bias 25 applied to the control grid of said modulator tube varies in accordance with the amplitude of the oscillations generated by said oscillator tube.

4. A circuit arrangement including an oscillator circuit, a modulator tube having a control 30 grid and a plate, means for energizing said oscillator and said modulator including a source of biasing potential for the control grid of said modulator tube, means for rectifying a portion of the immediate output of said oscillator and 35 means for applying said rectified output in series with said source of biasing potential as an additional bias.

5. A transmitter including an oscillator circuit, a modulator tube having a control grid and 40 a plate, means for energizing said oscillator and said modulator including a source of biasing potential for the control grid of said modulator tube, a rectifier immediately coupled to said oscillator circuit and means for connecting said rectifier in series with said source of biasing potential. 45
